BURIAL VAULT

John R. Madlem, Box 136A3, High Falls Road, R.D. 1,
Catskill, N.Y. 12414

Filed Nov. 19, 1970, Ser. No. 26,073

Term of patent 14 years

Int. Cl. D31

U.S. Cl. D19—1

FIG. 1 is a side, top and end perspective view of a burial vault, showing my new design;

FIG. 2 is a side elevational view, the opposite side being identical;

FIG. 3 is a top plan view viewed from line 3—3 in FIG. 2;

FIG. 4 is an end elevational view viewed from line 4—4 in FIG. 2, the opposite end being identical; and

FIG. 5 is a bottom plan view thereof, viewed from line 5—5 in FIG. 2.

I claim:

The ornamental design for a burial vault, as shown and described.
